[57] CLAIM

The ornamental design for a load hauling vehicle hitch
pin transducer for electronic load weighing, as shown.

DESCRIPTION

FIG. 1 is a perspective view of a load hauling vehicle
hitch pin transducer for electronic load weighing showing
my new design;

FIG. 2 is a front elevation view thereof;

FIG. 3 is a rear elevation view thereof;

FIG. 4 is a side elevation view thereof, the opposite side
being a mirror image of that shown;

FIG. 5 is a top plan view thereof; and

FIG. 6 is a bottom plan view thereof.

FIG. 1

FIG. 2

FIG. 4

FIG. 5

FIG. 3

FIG. 6
